UNITED STATES PATENT OFFICE

2,412,358

CORN PICKER

Andrew L. Roe, Bryan, Ohio, assignor of one-half
to Clarence Siebenaler, Edon, Ohio

Application October 4, 1943, Serial No. 504,922

2 Claims. (Cl. 56—18)

1

The present invention relates to new and useful improvements in corn pickers, and has for its primary object to provide, in a manner as herein-after set forth, a machine of this character which is adapted to be expeditiously mounted for operation on one side of a conventional tractor, motor truck or wagon.

Another very important object of the invention is to provide a corn picking or harvesting machine of the aforementioned character which embodies a unique construction, combination and arrangement of endless gatherers and snapping and husking rolls.

Other objects of the invention are to provide a corn picker of the character described which will be comparatively simple in construction, strong, durable, highly efficient and reliable in use, compact, light in weight, and which may be manufactured at low cost.

All of the foregoing and still further objects and advantages of the invention will become apparent from a study of the following specification, taken in connection with the accompanying drawings wherein like characters of reference designate corresponding parts throughout the several views, and wherein:

Figure 1 is a view in side elevation with a portion broken away, showing a corn picker constructed in accordance with the present invention mounted for operation on one side of a motor truck.

Figure 2 is a top plan view thereof.

Figure 3 is a plan view of the snapping and husking rolls.

Figure 4 is a sectional view taken on the line 4—4 of Figure 2.

Figure 5 is a view showing the drive for the snapping and husking rolls.

Figure 6 is a fragmentary view in elevation of one of the rolls and the adjacent conveyor, looking at the inner side thereof.

Figure 7 is a sectional view taken on the line 7—7 of Figure 2.

Figure 8 is a vertical view taken on the line 8—8 of Figure 1.

Referring now to the drawings in detail, it will be seen that reference character 1 designates generally an elevator. In the embodiment shown, in Figures 1 and 2, of the drawings, the elevator 1 is mounted at an inclination on one side of the body 2 of a motor truck 3 in any desired conventional manner as through the medium of one or more suitable hangers 4. A hanger 4' prime may take the form as best shown in Figure 1 of a substantially L-shaped member, the upright leg of

2

which terminates in a hook to overlie the top edge of the truck body 2.

The elevator 1 includes a pair of spaced, parallel, elongated, metallic housings 4 of substantially segmental cross-section, which housings are mounted on a frame structure 5. Pairs of spaced, parallel guides 6 are mounted in the lower, inner portions of the housings 4. Slots 7 in the inner walls of the housings 4 communicate with the inner guides 6.

Sprocket wheels 7' are journaled in the housings 4 adjacent the ends of the pairs of guides 6. Endless conveyor chains 8 are operable in the guides 6 and trained over the sprocket wheels 7'. Flights 9 are mounted at suitably spaced points on the chains 8. The upwardly moving flights 9 travel in the slots 7 and project between the housings 4. These flights, it will be observed, are staggered and overlap when moving upwardly, as illustrated to advantage in Figure 4 of the drawings. The endless chains 8 may be driven in any suitable manner. If a power plant is to drive the endless chains 8, a platform 10 for said power plant is suspended beneath the elevator 1.

Journaled in the frame structure 5 between the housings 4 is a pair of coating rolls 11. Each of the rolls 11 includes a metal front snapping section 12, a metal intermediate husking section 13, and a rubber rear husking section 14. The snapping and husking rolls 11, it will be observed, are below and adjacent the upwardly moving flights 9.

Gears 15 between the sections 12 and 13 connect the rolls 11 for operation in unison in opposite directions. A plate 16 is mounted above the gears 15. A gear 17 on a shaft 18 drives the adjacent gear 15. The shaft 18 is geared to a transverse shaft 19. A sprocket wheel 20 is loosely mounted on the shaft 19. A sprocket chain 21 is trained over the sprocket wheel 20 and a comparatively large sprocket wheel 22 on the adjacent rear wheel 23 of the motor truck 3. A clutch 24 which is splined on the shaft 19 is adapted to releasably connect the sprocket wheel 20 to said shaft.

A forked lever 25 on the inner side of the elevator 1 engages and disengages the clutch 24. An actuating rod 26, operable from the driver's compartment 27 of the motor truck 3, is connected to the lever 25.

A bracket 28 is removably mounted on the front portion of the vehicle body 2. Mounted on the bracket 28 is a toothed ring 29. A reversible hand lever 30 is journaled on the ring 29, the latch 31 of said hand lever being engageable with the toothed periphery of said ring for releasably securing said lever in adjusted position. A link

32 connects the hand lever 30 to a bracket 33 on the adjacent portion of the elevator 1 for raising and lowering said elevator. As best seen in Figure 8 of the drawings, the bracket 33 is coupled to the lower end portion of the link 32 by a pin and slot connection 34. Thus, the forward or lower end of the elevator 1 may have limited upward movement independently of the lever 30. Such movement is yieldingly resisted by a coil spring 35 on the link 32. Ground shoes 10 36 are provided on the lower end of the elevator 1.

Projecting rearwardly from the upper portion of the elevator 1 is a bracket or the like 37. A bowl or other receptacle 38 is rotatably mounted on the bracket 37 for receiving the ears of corn from the elevator 1. Projecting from the rotatably adjustable receptacle 38 is a chute 39 for discharging the ears into the body 2, or, if desired, into a vehicle accompanying the picker.

It is thought that the operation of the machine will be readily apparent from a consideration of the foregoing. Briefly, the inclined elevator 1 straddles the row to be harvested and the stalks are directed into said elevator by the outwardly curved snout portions 40 on the forward ends of the housings 4. The sections 12 of the rolls 11 snap the ears of corn from the stalks, which ears are carried up said rolls by the flights 9 on the endless chains 8. The husks are removed by the sections 13 and 14 of the rolls 11. When the husked ears reach the upper end of the elevator 1, they are dropped into the receptacle 38 and discharged by gravity through the chute 39 into the body 2 of the vehicle 3. In Figure 1 of the drawings, also Figure 2, the hand lever 30 is operable from the driver's compartment of the vehicle. If desired, this lever may be reversed and the removable bracket 28 mounted in the position shown in dotted lines in Figure 1 of the drawings, whereby said lever may be conveniently operated from within the body 2 for the purpose of raising or lowering the forward end of the elevator.

It is believed that the many advantages of a corn picker constructed in accordance with the present invention will be readily understood, and although a preferred embodiment of the machine is as illustrated and described, it is to be understood that changes in the details of construction and in the combination and arrangement of parts may be resorted to which will fall within the scope of the invention as claimed.

What is claimed is:

1. A corn picking machine of the character described comprising an inclined elevator adapted to be mounted for vertical swinging adjustment on one side of a vehicle, a bracket mounted on the vehicle adjacent the elevator, a toothed ring mounted on said bracket, a reversible lever pivotally mounted on the ring, a latch on the lever engageable with the teeth of the ring for releasably securing said lever in adjusted position, a link secured to said lever and having a pin and slot connection to the elevator for raising and lowering said elevator, said pin and slot connection permitting limited raising of said elevator independently of said link.

2. A corn picking machine of the character described comprising an inclined elevator and adapted to be mounted for vertical swinging adjustment on one side of a vehicle, a bracket mounted on the vehicle adjacent the elevator, a toothed ring mounted on said bracket, a reversible lever pivotally mounted on the ring, a latch on the lever engageable with the teeth of the ring for releasably securing said lever in adjusted position, a link secured to said lever and having a pin and slot connection to the elevator for raising and lowering said elevator, said pin and slot connection permitting limited raising of said elevator independently of said link, and resilient means surrounding said link normally biasing said elevator toward the extremity of said slot away from said lever.

ANDREW L. ROE.
